CLAIM

The ornamental design for an AUDIO INTERFACE as shown and described.

DESCRIPTION

FIG. 1 is a top, front, right side perspective view of an AUDIO INTERFACE, showing my design.

FIG. 2 is a bottom, rear, left side perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of an area labeled 9 in FIG. 1.

FIG. 10 is an enlarged view of an area labeled 10 in FIG. 1. The evenly spaced dashed broken lines depict portions of the Audio Interface that form no part of the claimed design. The dot-dash line circles depict the limits of the enlarged views and form no part of the claimed design.
